(57) **CLAIM**

What is claimed is an ornamental design for a junction light box, as shown and described.

DESCRIPTION

FIG. 1 is an upper front perspective view of a junction light box according to a first embodiment;

FIG. 2 is a lower front perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof;

FIG. 8 is a left side view thereof;

FIG. 9 is an upper front perspective view of a junction light box according to a second embodiment;

FIG. 10 is a lower front perspective view of the second embodiment;

FIG. 11 is a top view of the second embodiment;

FIG. 12 is a bottom view of the second embodiment;

FIG. 13 is a front view of the second embodiment;

FIG. 14 is a rear view of the second embodiment;

FIG. 15 is a right side view of the second embodiment; and,

FIG. 16 is a left side view of the second embodiment.

The broken lines in the figures depict portions of the junction light box that form no part of the claimed design.
